CLAIM

The ornamental design for an absorbent paper product dispenser, as shown and described.

DESCRIPTION

FIG. 1 is a perspective view showing our new design for an absorbent paper product dispenser;

FIG. 2 is a front view of the embodiment of FIG. 1;

FIG. 3 is a back view of the embodiment of FIG. 1;

FIG. 4 is a right side view of the embodiment of FIG. 1;

FIG. 5 is a left side view of the embodiment of FIG. 1;

FIG. 6 is a top view of the embodiment of FIG. 1;

FIG. 7 is a bottom view of the embodiment of FIG. 1; and,

FIG. 8 is a perspective view showing our new design for an absorbent paper product dispenser hanging from another dispenser and holding a roll of absorbent paper product. In the figures, the broken lines represent unclaimed subject matter and form no part of the claim.

The dot-dashed broken lines in FIG. 8, show a roll and an additional hook holder, represent environmental structure, and form no part of the claimed design.

The evenly dashed broken lines, represent a portion of the absorbent paper product dispenser, that form no part of the claimed design.
